(57) **CLAIM**

The ornamental design for a container with surface ornamentation, as shown and described.

DESCRIPTION

The present application file contains at least one drawing executed in color. Copies of this patent or patent application publication with color drawing(s) will be provided by the Office upon request and payment of the necessary fee.

FIG. 1 is a perspective view of a container with surface ornamentation embodying our new design;
FIG. 2 is a front view thereof;
FIG. 3 is a right side view thereof;
FIG. 4 is a rear view thereof;
FIG. 5 is a left side view thereof;
FIG. 6 is a top view thereof;
FIG. 7 is a bottom view thereof;
FIG. 8 is a perspective view of a second embodiment of a container with surface ornamentation embodying our new design;
FIG. 9 is a front view thereof;
FIG. 10 is a right side view thereof;
FIG. 11 is rear view thereof;
FIG. 12 is a left side view thereof;
FIG. 13 is a top view thereof;
FIG. 14 is a bottom view thereof;
FIG. 15 is a perspective view of a third embodiment of a container with surface ornamentation embodying our new design;
FIG. 16 is a front view thereof;
FIG. 17 is a right side view thereof;
FIG. 18 is rear view thereof;
FIG. 19 is a left side view thereof;

FIG. 20 is a top view thereof;
FIG. 21 is a bottom view thereof;
FIG. 22 is a perspective view of a fourth embodiment of a container with surface ornamentation embodying our new design;
FIG. 23 is a front view thereof;
FIG. 24 is a left side view thereof;
FIG. 25 is rear view thereof;
FIG. 26 is a right side view thereof;
FIG. 27 is a top view thereof;
FIG. 28 is a bottom view thereof;
FIG. 29 is a perspective view of a fifth embodiment of a container with surface ornamentation embodying our new design;
FIG. 30 is a front view thereof;
FIG. 31 is a left side view thereof;
FIG. 32 is rear view thereof;
FIG. 33 is a right side view thereof;
FIG. 34 is a top view thereof; and,
FIG. 35 is a bottom view thereof.

In the drawings, the broken lines depict environmental subject matter only that forms no part of the claim.
